UNITED STATES PATENT OFFICE.

DAVID CRYSTAL AND MAX TISCHLER, OF NEW YORK, N. Y.

DESIGN FOR A SKIRT.

No. 38,953.

Specification for Design.

Patented Dec. 17, 1907

Application filed September 4, 1907. Serial No. 391,408. Term of patent 3½ years.

To all whom it may concern:

Be it known that we, DAVID CRYSTAL and MAX TISCHLER, citizens, respectively, of the United States, residing at New York city, county and State of New York, have invented a new, original, and ornamental Design for a Skirt.

The design is illustrated in the accompanying drawing and shows a side elevation thereof.

We claim:

The ornamental design for a skirt as shown.

DAVID CRYSTAL.
MAX TISCHLER.
